UNITED STATES PATENT OFFICE

JOHN F. O'CONNOR, OF CHICAGO, ILLINOIS, ASSIGNOR TO W. H. MINER, INC., OF CHICAGO, ILLINOIS, A CORPORATION OF DELAWARE

CAR CONSTRUCTION

Application filed July 27, 1928. Serial No. 295,655.

This invention relates to improvements in car construction.

One object of the invention is to provide means for connecting the body and truck bolsters of a railway car, including a sectional center pin member composed of a plurality of plate-like elements having shouldered engagement at opposite ends with the body and truck bolsters, respectively.

Another object of the invention is to provide a center locking pin arrangement for body and truck bolsters having center pin receiving openings, wherein the connecting pin comprises a plurality of plate-like sections which may be readily attached to or removed from the bolsters, as desired, the plate-like sections being adapted to be assembled in succession with the bolsters and forming, when assembled, a complete pin member, headed at opposite ends, having shouldered engagement with the bolsters to prevent separation of the same, the openings in the bolsters being of such a shape as to permit insertion of the plate-like members in one position, the plate-like members being rotatable about the axis of the assembled pin to bring all of the sections thereof into shouldered engagement with the bolsters, locking means being provided to prevent relative rotation of the assembled pin and one of the bolsters to hold said sections against disengagement from the shoulders of the bolsters.

Other and further objects of the invention will more clearly appear from the description and claims hereinafter following.

In the drawing, forming a part of this specification, Figure 1 is a vertical sectional view through the body and truck bolsters of a railway car, illustrating my improvements in connection therewith. Figure 2 is a top plan view at the central portion of the structure shown in Figure 1. Figure 3 is a bottom plan view of the construction illustrated in Figure 1, at the central portion of the truck bolster. And Figure 4 is a detailed perspective view of one of the plate members forming a section of the center locking pin of my improved construction.

In said drawings, 10 indicates a portion of the body bolster of a railway car and 11 a

portion of the cooperating truck bolster. The body bolster is provided with a hollow, sleeve-like section 12 which receives the upper portion of the locking center pin and a depending annular bearing member 13 cooperating with an annular bearing seat 14 formed in a bearing plate 15 seated in a pocket 16 at the top of the truck bolster 11, a filler or shim member 17 being interposed between the bearing plate 15 and the top of the bolster 11. The bolster 11 is provided with a center pin receiving opening 18 and the bearing plate 15 and shim member 17 are also provided with openings aligned with the opening 18 and the opening of the sleeve section 12 of the body bolster.

In carrying out my invention, I employ a sectional center locking pin A, composed of four heavy plate-like members 19-19 and 20-20, which, when assembled, form the complete locking pin; a pair of locking blocks B-B; and a cotter pin C for locking the blocks B-B to the sectional pin A. I further form the center pin receiving openings of the bolster of such a cross section as to facilitate the entering of the sections of the pin A.

The four sectional plate-like members 19-19 and 20-20 of the pin are of similar design, but the plate-like members 20 are of greater width than the members 19. Each plate-like member comprises a main body portion of substantially rectangular cross section which is elongated so as to form a shank portion of the pin. At the opposite ends, each plate is provided with a pair of aligned laterally projecting lugs 21-21, the lugs at each end forming in effect a head portion. As shown in Figure 1, the head portions 21 at the upper ends of the plate members cooperate with the flat end face of the sleeve-like section of the bolster 10, thereby supporting the assembled members which form the center locking pin A against downward movement. The head portions 21 at the opposite ends of the plate cooperate with the bottom face of the middle section of the truck bolster in a similar manner so as to prevent upward movement of the pin and hold the

same assembled with the body and truck bolsters and lock the bolsters together.

As clearly illustrated in Figure 1, the aligned center pin receiving openings of the body and truck bolsters are of the same diameter and each opening has the side wall at diametrically opposite portions slotted, as indicated at 22-22. The slots or openings 22 are of such a width as to permit the head sections 21 of the plate members 20 to pass freely therethrough in assembling the plate members with the bolsters. As most clearly illustrated in Figures 2 and 3, the slots 22 are to one side of the diametrical center plane of the pin receiving openings of the bolsters.

As hereinafter more clearly pointed out, the slots 22 are offset to one side of the center of the openings in the bolsters to facilitate insertion of the plate member 20, which is last applied in assembling the pin and which plate member in effect forms a key plate.

The two locking blocks B are provided to prevent rotation of the sectional locking pin A after the parts thereof have been assembled and the pin is in the position shown in the drawings. Each locking block comprises a bottom section having a flat inner face which abuts the outer side of one of the plates 19 and a curved face on the outer side which fits the curved side wall of the pin receiving opening of the sleeve 12. Each block B is also provided with an outwardly projecting lug member 23, adapted to fit within the slot 22 at the corresponding side of the pin receiving opening of the sleeve 12. Each block is also provided with an upstanding section 24 provided with a cotter pin receiving opening 25. Each of the plate members forming the sectional center locking pin A is also provided with a cotter pin receiving opening 26 at the upper end thereof. When the sectional locking pin A is assembled and disposed in the position shown in Figures 1, 2 and 3, and the blocks have been inserted in the pin receiving opening of the sleeve 12 at opposite sides of the sectional pin A with the lugs 23 of the locking blocks engaged within the slots 22, the locking blocks are secured to the sectional pin A by means of the cotter pin C, which is inserted through the aligned openings 25 of the locking blocks and 26 of the plate members. As will be evident, the locking blocks are thus secured to the sectional pin A and rotation of the pin is prevented by the locking blocks which have the lugs thereof interlocked with the slots 22 of the sleeve 12.

In assembling the parts of my improved sectional center locking pin to connect the bolsters, the parts of the same are in the present instance inserted through the upper end of the sleeve section 12 of the body bolster, inasmuch as the invention is illustrated in connection with body and truck bolsters associated with the six-wheel type of truck, the central axle of which is shown in dotted lines

beneath the truck bolster 11 and is designated by 27. As will be evident with the axle member 27 located immediately below the central portion of the truck bolster and in vertical alignment with the center locking pin receiving openings of the bolsters, it is not possible to insert the pin sections through the bottom of the opening in the truck bolster. However, it will be obvious that when my improved center pin arrangement is employed in connection with the bolsters of a car provided with other than six-wheel trucks, the parts of the pin may be inserted through the bottom end of the pin receiving opening in the truck bolster and the locking blocks may be associated with the last named bolster.

In applying the sectional center locking pin A to the bolsters 10 and 11, one of the narrower sections 19 is first applied by inserting the same within the opening of the sleeve 12 through the upper end of the sleeve, first bringing the lugs 21 of the section in alignment with the slots 22 of the center pin receiving openings of the bolsters. After the bottom lugs 21 of the plate 19 referred to have been passed through the center pin receiving openings of the bolsters, the plate is displaced to one side of the slots 22 so as to overlap the lugs 21 at the opposite ends of the plate with the abutment faces of the body and truck bolsters.

The second plate 19 is then applied in a similar manner and displaced laterally so as to dispose the plate on the opposite side of the pin receiving opening to that occupied by the plate 19 first inserted. One of the wider plates 20 is then inserted in a similar manner and displaced to one side of the slots 22, thus leaving the slots open to permit insertion of the last plate forming the sectional center locking pin. The last plate 20, which in effect forms the key plate to hold the remaining plates separated and the pin in assembled relation, is then inserted in the pin receiving openings in the same manner as the other plate members, and after the lugs 21-21 at the lower end of the key plate have been brought in alignment with the lugs 21-21 at the bottom end of the remaining plates the assembled sectional center locking pin A is rotated bodily through an angle of ninety degrees, thereby bringing the same into the position shown in Figures 1, 2 and 3. As will be evident when the sectional locking pin A is thus positioned, all of the plate members thereof have shouldered engagement with the abutment faces on the body and truck bolsters thereby preventing separation of the bolsters under all conditions.

To lock the sectional pin A in position so that the same will not rotate with respect to one of the bolsters, the two locking blocks B are applied to opposite sides of the assembled locking pin and the lugs 23 of the locking blocks engaged within the slots 22 of the

sleeve 12 of the bolster 10, as hereinbefore pointed out. The locking blocks are then secured to the plate members forming the sectional pin by the cotter pin C.

5 When it is desired to remove the sectional locking pin so that the bolsters may be separated, it is merely necessary to first remove the locking blocks B and then rotate the locking pin A through an angle of ninety degrees 10 to bring one of the plates 20 in alignment with the slots 22. The plate 20 may then be driven out and the remaining plates displaced laterally so as to bring the same in alignment with the slots 22 and the latter may then be 15 driven out in a similar manner.

10 While I have herein shown and described what I consider the preferred manner of carrying out my invention, the same is merely illustrative and I contemplate all changes 20 and modifications which come within the scope of the claims appended hereto.

I claim:

1. In car construction, the combination 25 with body and truck bolsters provided with aligned center pin receiving openings; of a sectional locking pin connecting said bolsters, said pin comprising a plurality of sections each headed at opposite ends and said heads at opposite ends of each section having shouldered engagement with said bolsters, respectively, to prevent removal of the pin and separation of the bolsters.

2. In car construction, the combination 35 with body and truck bolsters provided with aligned center pin receiving openings; of a sectional locking pin connecting said bolsters, said pin comprising a plurality of plate-like sections each headed at opposite ends and having shouldered engagement with said bolsters, respectively, to prevent removal of the pin and separation of the bolsters, said plates including a key plate member headed at opposite ends, said key plate member being insertible between the remaining plates, the locking pin receiving openings of the bolsters being formed of a cross section to permit insertion of said locking key plate, when in one position, said sectional pin being rotatable to displace said key plate and the headed 40 portions thereof to bring the latter in shouldered engagement with the bolsters.

3. In car construction, the combination 45 with body and truck bolsters having aligned center pin receiving openings, the walls defining said openings being slotted at opposite sides; of a sectional locking pin connecting said bolsters, said locking pin including a plurality of plate-like sections and a key plate member, said plate-like sections and key 50 plate member being headed at opposite ends, said head portions having shouldered engagement with the body and truck bolsters, respectively, said key plate member being insertible through the slotted sections of the 55 walls of the pin receiving openings between the

said plate-like sections to spread the same apart, and said sectional pin, when assembled, being rotatable to bring the head portions of all of the sections thereof in shouldered engagement with both of the bolsters.

4. In car construction, the combination 60 with body and truck bolsters having aligned center pin receiving openings, the walls defining said openings being slotted at opposite sides; of a sectional locking pin connecting said bolsters, said locking pin including a plurality of plate-like sections and a key plate member, said plate-like sections and a key plate member being headed at opposite ends, said head portions having shouldered engagement with the body and truck bolsters, respectively, said key plate member being insertible through the slotted sections of the walls of the pin receiving openings between the 65 said plate-like sections to spread the same apart, and said sectional pin, when assembled, being rotatable to bring the head portions of all of the sections thereof in shouldered engagement with both of the bolsters; and means for locking said sectional locking pin against rotation with respect to one of said bolsters.

5. In car construction, the combination 70 with body and truck bolsters having aligned center pin receiving openings of circular cross section, the walls defining said openings being slotted at opposite sides; of a sectional locking pin connecting said bolsters, said locking pin including a plurality of plate-like sections of substantially rectangular cross section, and a key plate also of substantially rectangular cross section, said plate sections and key plate being headed at opposite ends, said head portions having shouldered engagement with the body and truck bolsters, respectively, said key plate being insertible through the slotted sections of the walls of the pin receiving openings between the plate-like sections to spread the same apart and said sections of the pin, when assembled, being rotatable to bring the head portions of all of the sections thereof in shouldered engagement with said body and truck bolsters.

6. In car construction, the combination 75 with body and truck bolsters having aligned center pin receiving openings of circular cross section, the walls defining said openings being slotted at opposite sides; of a sectional locking pin connecting said bolsters, said locking pin including a plurality of plate-like sections of substantially rectangular cross section and a key plate also of substantially rectangular cross section, said plate sections and key plate being headed at opposite ends, said head portions having shouldered engagement with the body and truck bolsters, respectively, said key plate being insertible 80 through the slotted sections of the walls of the pin receiving openings between the plate-

like sections to spread the same apart and said sections of the pin, when assembled, being rotatable to bring the head portions of all of the sections thereof in shouldered engagement with said body and truck bolsters; and locking members fitting between the outer plates forming the sectional locking pin and the walls of the corresponding pin receiving opening and having lugs seated in said slots to prevent turning of the locking blocks in said pin receiving opening.

7. In car construction, the combination with body and truck bolsters having aligned center pin receiving openings of circular cross section, the walls defining said openings being slotted at opposite sides; of a sectional locking pin connecting said bolsters, said locking pin including a plurality of plate-like sections of substantially rectangular cross section and a key plate also of substantially rectangular cross section, said plate sections and key plate being headed at opposite ends, said head portions having shouldered engagement with the body and truck bolsters, respectively, said key plate being insertible through the slotted sections of the walls of the pin receiving openings between the plate-like sections to spread the same apart and said sections of the pin; when assembled, being rotatable to bring the head portions of all of the sections thereof in shouldered engagement with said body and truck bolsters; locking members fitting between the outer plates forming the sectional locking pin and the walls of the corresponding pin receiving opening and having lugs seated in said slots to prevent turning of the locking blocks in said pin receiving opening; and means for securing the locking members to the sections of the center pin.

In witness that I claim the foregoing I have hereunto subscribed my name this 25th day of July, 1928.

JOHN F. O'CONNOR.
